UNITED STATES PATENT OFFICE

KNUD GEORG MELDAHL, OF FREDRIKSSTAD, NORWAY

STEAMSHIP WITH THE MAIN BOILER MOUNTED ON A DECK OR PLATFORM AT SOME HEIGHT ABOVE THE BOTTOM OF THE SHIP OR THE TANK TOP

Application filed October 16, 1931, Serial No. 569,328, and in Norway September 2, 1931.

In steamships in which the main boilers are mounted on a deck or platform at some height above the bottom of the ship so that a free space is obtained below the boiler room, it is as a rule advantageous to use this room for bunkers, auxiliary machinery or the like, since, if the room is used as a cargo hold, it is often difficult to arrange the cargo hatch as near to the end bulkhead of the room as desirable.

Where the said space is used as a coal bunker, the boilers will hinder the location of the bunker hatches or trunks at convenient points for filling of the bunker. According to the present invention this difficulty is avoided by carrying one or more bunker trunks down between the boilers, the latter being for this purpose located at a somewhat greater distance apart than usual, the common flue or uptake for the boilers being made correspondingly longer. It is thus possible to arrange the trunks at the most suitable place in the middle of the bunker so that little or no trimming of the coal is necessary in order to completely fill the bunker.

The trunk further may be provided with a varying cross section at different points in its length in order to facilitate filling and a further reduction of the trimming. For instance, the trunk may be widened below the center line of the boiler.

The drawing illustrates an embodiment of the invention, Fig. 1 is a longitudinal section through the engine room and boiler room of the ship, and Fig. 2 shows the arrangement in a horizontal section on the level of the boiler room.

Part 1 is the engine room, 2 the boiler room and 3 the bunker below the same. As will be seen, the boilers 4, 5 are placed at some distance one from the other, with an extended uptake 6, and the filling trunk 7 is carried down between the boilers centrally to the bunker.

Having now particularly described and ascertained the nature of my said invention and in what manner the same is to be performed, I declare that what I claim is:

1. In a steamship, the combination with a plurality of main boilers mounted on a deck

or platform at some height above the bottom of the ship, said boilers being arranged in spaced relation of a bunker below the boilers, and at least one filling trunk for the bunker carried down between the boilers.

2. An arrangement as claimed in claim 1, characterized in that the cross-section of the trunk increases below the center line of the boilers in order to facilitate filling of the bunker.

In testimony whereof I hereunto affix my signature.

KNUD GEORG MELDAHL.
